UNITED STATES PATENT OFFICE.

FREDERICK J. LEMLEY, OF CHICAGO, ILLINOIS.

FRICITION-CLUTCH.

1,184,542.

Specification of Letters Patent. Patented May 23, 1916.

Application filed April 2, 1915. Serial No. 18,789.

To all whom it may concern:

Be it known that I, FREDERICK J. LEMLEY, a citizen of the United States, residing at Chicago, in the county of Cook and State of Illinois, have invented certain new and useful Improvements in Friction-Clutches, of which the following is a specification.

The present invention has reference to certain improvements in friction clutches of that general type shown in Letters Patent of the United States No. 1,055,192, issued March 4, 1913. In the said Letters Patent, there are disclosed constructions making use of toggle levers which are so pivoted as to swing toward and from the axis of rotation. These levers serve when in their extended position to produce a clamping relationship between the driving and driven elements for the purpose of frictionally connecting these parts together. Ordinarily the levers are connected to the driving element and rotate continually. There is thus produced or set up in them centrifugal forces, which forces tend to throw the levers out in their extended position, thereby producing the clamping action. One of the objects of the present invention is to provide means for so locking the parts when in their unclutched position that the levers cannot throw out under the centrifugal action into the extended or clutching position. This will prevent an automatic clutching action from taking place at a time when it is not desired.

Another object of the invention is to improve the construction of the clutch as a whole by so arranging the parts that a greater amount of mechanical advantage can be secured for swinging the levers. This will enable the operator to secure an extremely tight and firm clutching action without the necessity of exerting a very large operating force. Ordinarily, in a device of this kind, the parts may be so arranged that a considerable amount of movement of the operating handle can be secured, and the present object has reference to the application of such movement in the most advantageous manner for the production of the clamping action.

Other objects and uses will appear from a detailed description of the invention which consists in the features of construction and combination of parts hereinafter described and claimed.

Referring to the drawings: Figure 1 shows

a cross section through one form of clutch construction embodying the features of the present invention; Fig. 2 is an end view of the construction shown in Fig. 1 being taken on the line 2-2 of Fig. 1, looking in the direction of the arrows; Fig. 3 is a section taken on the line 3-3 of Fig. 1, looking in the direction of the arrows, being on an enlarged scale; Fig. 4 is an enlarged detail view of a modified construction of locking mechanism; Fig. 5 is a section taken on the line 5-5 of Fig. 4, looking in the direction of the arrows; and Fig. 6 is a modified form of connection between the sliding collar and the toggle links.

Referring to the several figures, I have shown a clutch construction which is adapted to control the delivery of power from the shaft 6 to the pulley 7. The shaft 6 rotates continuously, and the clutch serves to control the connecting and disconnecting of the pulley to the shaft. On the shaft is drivingly mounted a sleeve 8 which has the annular flange 9. The pulley has the sleeve 10 which is rotatably mounted on the sleeve 8 and has the annular flange 11. The collar 12 is slidably mounted on the sleeve 8 outside of the sleeve 10, and the extreme end of the sleeve 8 carries the collar 13. This latter collar is connected to the sleeve 8 in any desired manner as by a threaded connection. It will be observed that the collar 13 and flange 9 remain a fixed distance apart, whereas the sleeve 12 may be slid back and forth with respect to the flange 12 and the collar 13.

The bell cranks 14 are pivoted to the collar 12. Each bell crank has the short arm 15, which may engage the inner face of the collar 13, and has the long arm 16 which may swing toward and away from the axis of rotation.

On the shaft 6 or an extension thereof, is slidably mounted the sleeve 17. The collar 12 and the sleeve 17 rotate with and are preferably driven by the shaft 6, so that they maintain a fixed angular position with respect to each other. The long arms 16 of the bell cranks are connected to the sleeve 17 by means of links, so that, when the sleeve is forced toward the collar 13, the arms 16 of the bell cranks will be forced away from the axis of rotation, thereby tilting the bell cranks, causing the short arms 15 to cooperate with the collar 13, and thereby engaging said arm against the collar to carry the col-

lar 12 toward the flange 9. This will serve to clamp the driven element between the collar 12 and flange 9, thus establishing the driving connection.

5 As a simple means for forcing the sleeve 17 back and forth, I have shown said sleeve as provided with an annular slot 18. Within this slot is seated the inner ring 19 of a hand wheel 20. The hand wheel may 10 main stationary while the sleeve 17 rotates, but by forcing the hand wheel back and forth the sleeve will be controlled in the desired manner.

The constructions thus far outlined substantially conform to the disclosures of the aforementioned Letters Patent No. 1,055,192. In the present case, I have so formed the links connecting the collar 17 with the bell crank arm 16 as to materially increase the 20 mechanical advantage exerted between the collar 17 and the bell cranks. In the present case, I have provided the links 21 connecting the arms 16 to the sleeve 17. In the constructions of the said Letters Patent, the 25 links do not pass the axis of rotation, but each link lies entirely to one side of the axis of rotation. As a result the possible length of the links is very limited. In the present case, I have so related the parts that each 30 link may be carried from the corresponding arm 16 to a connection with the sleeve 17 at the opposite side of the axis of rotation. The result is that the length of the links is very materially increased.

35 Referring to Fig. 3, the preferred form of the links 21 and their connection to the sleeve 17 will be readily understood. Each of the bell cranks 16 preferably lies in the plane which includes the axis of rotation.

40 Each link is preferably bent or offset in such a way that its operating end 22 may pass the shaft. In the particular construction illustrated, the sleeve 17 has its opposite sides flattened. The links lie against 45 these flattened portions. The sleeve has a pair of lugs 23, which provide slots or recesses for the accommodation of the end portions 22 of the links. A pin 24 is run through each side of the sleeve and through 50 the end 22 of the corresponding link. Each pin 24 has the enlarged head 25 seating into a recess of the sleeve, and a cotter pin 26 may be extended through the other end of each pin 24 to hold the same in place. In 55 the arrangement just described, each of the links will find a very firm and secure bearing with respect to the sleeves, being supported on its inner face by the flattened portion of the sleeve and on its outer face by 60 the presence of the corresponding lug 23.

In the arrangement shown in Fig. 6, the lugs 23 are dispensed with and each link is supported only by the flattened surface of the sleeve.

65 Manifestly, with the arrangements above

described, the length of the links may be very materially increased, the permissible increase amounting from 50 to 100%. This will enable the production of a very much more powerful clutching action with the exertion of a given amount of force on the hand wheel. It will be understood that the hand wheel does not serve the function of rotating any part, but simply serves as a convenient means for forcing the sleeve 17 back and forth. 75

Referring to Figs. 2 and 5, the plate 27 is connected to the front portion of the hand wheel, as by means of the screws 28 which pass into the arms 29 of the hand wheel. On 80 one side of the shaft or an extension thereof, this plate is provided with an enlargement 30, within which a pin 31 is slidingly mounted. This enlargement has a radial opening or bore, the outer portion of which communicates with a front slot 31. A pin 32 is slidingly mounted within the bore, and has a thumb block or lug 33 which extends through the slot, and by means of which the movements of the pin may be controlled. The outer end of the bore is closed by a plug 34, and a spring 35 is interposed between the pin and plug so as to force the pin toward the axial center. 85

In the arrangement shown in Fig. 1, the shaft 6 is illustrated as terminating within the sleeve 17, there being an extension pin 36 of relatively small size projecting from the end of the shaft. The outer end of the sleeve slides on this extension pin. The pin 36 terminates at such point that, when the hand wheel is pulled out to effect the unclutching operation, the pin 32 may be forced down outside of the end of the pin 36, so that by this engagement the sleeve will be prevented from sliding in toward the pulley under the influence of centrifugal force generated in the arms 36. When the operator desires to clutch the parts together, he may disengage the pin 32 by manipulation 100 of the thumb piece 33. 105

In the arrangement shown in Fig. 4, I have illustrated the pin 36 as being provided with a cone-shaped sleeve 37. In this case, the engagement of the pin is against the outer shouldered face in this sleeve instead of against the end of the pin 36 or the shaft. 115

It will be understood that I do not limit myself to the features of the invention particularly illustrated and described except as 120 I may do so in the claims, but that, on the other hand, I contemplate within the scope of my invention any equivalent constructions operating in equivalent manners to produce equivalent results. 125

I claim:

1. In a device of the class described the combination with a driving element having a fixed abutment and a slideable abutment, and a driven element mounted on the driv- 130

ing element between said fixed and slidable abutments, of an annular collar secured to the driving element at a given distance from the fixed abutment, toggle levers on the slid-
5 able abutment having arms adapted to en-
gage said collar, a sleeve slidably mounted with respect to the collar, and links extending from the free arms of the toggle levers past the axis of rotation of the driving mem-
10 ber to points of connection with said sleeve, whereby said links are of greater length than the radial distance from the axis of rotation to the free arms of the toggle levers.

2. In a device of the class described the
15 combination with a driving element having a fixed abutment and a slidable abutment, and a driven element loosely mounted on the driving element between said fixed and slid-
20 able abutments, of an annular collar secured to the driving element at a given distance from the fixed abutment, toggle levers pivot-
25 ally connected to the slidable abutment, a sleeve slidably mounted with respect to the annular collar whereby it may be forced to-
ward and away from the same, and links connecting the free arms of the toggle levers to the sleeve at points farther removed from the free arms of the toggle levers than the radial distance from the toggle levers to the
30 axis of rotation.

3. In a device of the class described the
combination with a driving element having two fixed abutments with annular surfaces facing each other, a driven element loosely

mounted on the driving element between 35
said abutments, and a slidable abutment slid-
ably mounted on the driving element be-
tween one of the abutments and the driven
40 element, of a sleeve slidably mounted with
respect to the driving element, toggle levers 45
pivotally connected to the slidable abutment
and each having an arm in position to en-
gage the adjacent fixed abutment, and links
connecting the free arms of the toggle levers
45 with the sleeve at points removed from the
free arms of the toggle levers a greater dis-
tance than the radial distance from the tog-
gle levers to the axis of rotation.

4. In a device of the class described the
combination with a driving element having 50
a clutch face, and a driven element movably
mounted adjacent to said clutch face and
adapted to engage the same, of a sleeve mov-
ably mounted with respect to the driving
55 element, means for carrying the driven ele-
ment into engagement with the driving ele-
ment, and an operative connection from the
sleeve past the center of rotation to the
carrying means for the purpose of connect-
60 ing the same to the sleeve, whereby said
operative connection is of greater length
than the radial distance from the axis of ro-
tation to the carrying means, substantially as
described.

FREDERICK J. LEMLEY.
